UNITED STATES PATENT OFFICE.

ELMER A. THURSTON, OF NORFOLK, NEBRASKA, ASSIGNOR OF ONE-HALF TO JAMES A. MASON, OF NORFOLK, NEBRASKA.

FLEXIBLE PITMAN.

1,313,764.

Specification of Letters Patent.

Patented Aug. 19, 1919.

Application filed December 5, 1918. Serial No. 265,425.

To all whom it may concern:

Be it known that I, ELMER A. THURSTON, a citizen of the United States, at present residing at Norfolk, in the county of Madison 5 and State of Nebraska, have invented certain new and useful Improvements in Flexible Pitmen, of which the following is a specification.

The improvement relates to that class of 10 inventions found particularly useful on sewing machines and the like where considerable difficulty is encountered in the use of ordinary pitmen because of jarring and knocking of the parts and the stopping of the machine on a dead center.

To this end, I have designed a flexible pitman which entirely does away with all jarring, knocking and continuous adjusting of parts and also the danger of the machine 15 stopping on a dead center with its possible consequence of reversing the machine and breaking a needle or the ruining of the material being worked and which may be readily attached to most of the conventional 20 types of machines in use.

With other objects in view that will presently appear, my invention comprises those novel details of construction and combination of parts specifically pointed out in the 25 appended claims and illustrated in the accompanying drawings, in which:

Figure 1 is a side elevation of my invention as operatively applied to a sewing machine.

Fig. 2 is a detail side view and part section of the parts that constitute my improved attachment.

Fig. 3 is a diagrammatical side view and 35 illustrates the manner in which the pitman 40 operates to throw its coöperating crank pin past its upper dead center.

Fig. 4 is a similar view illustrating the passing of the lower dead center.

In its practical application, my improved 45 pitman may be utilized on any machine embodying the usual power wheel 2 and its crank pin 20 and the treadle 3 or other parts which would serve the same purpose on that particular machine.

In the drawings, the pitman is shown as 50 applied to a sewing machine 1 and includes a stout helical spring 4 and a rigid rod 5. The spring, which forms an essential feature 55 of my improvement, is spindle shaped, bunched or enlarged midway its length as at

4^a and tapering gradually to its straight reduced ends 4^b, the purpose of which will presently appear.

For effecting the tight connection of the helical spring to its coöperating rigid rod 60 member 5, the said rod is provided at its lower end with a threaded portion 50 and an end abutment 5^a so designed as to screw into and abut the upper reduced end 4^a of the spring 4.

The upper or crank engaging end of the rod 5 is threaded as at 51 and adapted to be threaded into the threaded aperture 22 of a journal block 21.

A lock nut 52 being provided to coöperate 70 with the journal block 21, it will be readily seen that any slight adjustment necessary, when first applying the device, may be readily effected.

I wish it here understood, however, that 75 after the first application and adjustment of the pitman, no further adjustment will ever be necessary.

For connecting the spiral spring member 80 to the treadle 3 of the machine, I have provided a nipple 6 designed to thread into the lower reduced spiral 4^a of the said spring which includes a collar or abutment 61 serving the dual purpose of abutting the lower 85 end of the spring and forming a shoulder to engage the treadle 3 when the nipple portion 6 is inserted in the aperture 30 provided therefor in the treadle and is rigidly fastened therein, when the nut 7 is screwed home on the projecting threaded portion 62. 90

With the parts thus connected and operatively applied as illustrated in Figs. 1, 3 and 4, it will be seen that the device loses none of the advantages of a strictly rigid pitman and still readily operates to do away 95 with the faults thereof and accomplishes every purpose for which it is designed.

With reference to Fig. 2 of the drawings, it will be seen that the stout spring has its 100 spirals closely wound so as to leave but a very slight space between the adjacent coils, thus allowing for the necessary lateral flexibility of the same and also for the rigidity necessary on the power stroke up and down, 105 as will presently appear.

Owing to the peculiar construction and connection of the device, as clearly illustrated in Figs. 3 and 4 of the drawings, it will be readily seen that, owing to the lateral flexing of the spring portion of the pitman, 110

it is impossible for the machine to knock, jar or stop when passing a dead center.

The pitman member as it passes the center, when traveling on the up stroke, as indicated in Fig. 3, flexes the spring at its bulged portion, as shown, and tends to throw the crank members past the dead center (indicated in dot and dash lines) from the point A to the point B where the down power stroke will start and the spring then would start to flex, as indicated in Fig. 4, and accomplish the smooth passing of the crank from the point A' to B' over the lower dead center, and so on.

I want it here understood that this purpose is accomplished smoothly and evenly and in nowise causes an intermittent jerking of the power wheel.

To those experienced in the use of machines, another difficulty is known other than the stopping of the machine when in operation and that is encountered when, after the machine has been purposely brought to a stop, it is again sought to start it. In ordinary machines, the treadle, pitman and crank will in this case gravitate to the lower dead center and it is then necessary that the operator furiously spin the hand wheel and apply foot power just at the right interval to again put the machine in motion.

My device entirely does away with this objectionable feature, since the parts are so designed and operate so that it is impossible for the crank to stop on the lower (or upper) dead center, since the flexing of the spring positively throws it past these centers and, in the use of my pitman, the crank would always stop at a point such as indicated in Fig. 1 or as in dotted lines on Fig. 4 according to the strength and rigidity of the spring, so that to start up the machine, all that is necessary is to apply pressure to the heel portion of the treadle, thus making it entirely unnecessary to use the hands at any time, consequently making careful work more safe and easier.

What I claim is:

1. A pitman comprising a rod section hav-

ing provision at one end for connection to a power wheel, and a spring section secured to and forming a continuation of the rod section, said spring section comprising a helical coil spring having its convolutions in close juxtaposition, one end of said helical coil spring being firmly secured to the adjacent end of said rod section, and a stud firmly secured in the other end, the said stud being adapted to be fastened to a treadle or other operating device.

2. A pitman consisting of a rod, a helical spring whose coils or convolutions are of a greater diameter midway between the two ends than they are adjacent to the ends, a stud having a threaded shank onto which one end of said spring is screwed, said rod having a threaded shank onto which the other end of said spring is screwed, substantially as shown and described.

3. In combination with the rotatable power crank and the reciprocable treadle, of a pitman connecting the aforesaid parts, said pitman comprising a rod section pivoted to the crank and a spring section rigidly secured to the treadle, said spring section comprising a helical coil spring, the diameter of which is greater toward the middle than at the ends, and the coils of which normally lie in close juxtaposition, said helical spring and said rod section being rigidly connected end to end.

4. A pitman consisting of a rod, a stud and a helical coil spring, said rod, said spring and said stud being in longitudinal alinement, said spring comprising a coil, one end of which is wound around a portion of said rod and the other end of which is wound around a portion of said stud, the coils of the spring between the ends thereof being of gradually increasing diameter toward the midlength of the spring whereby the greatest diameter of the spring will be approximately midway between the ends of the spring substantially as shown and described.

ELMER A. THURSTON.
